UNITED STATES PATENT OFFICE.

OTTO J. NIENOW, OF MERRILL, WISCONSIN.

BOBSLED.

Application filed February 13, 1922. Serial No. 536,263.

To all whom it may concern:

Be it known that I, Otto J. NIENOW, a citizen of the United States, residing at Merrill, in the county of Lincoln and State 5 of Wisconsin, have invented certain new and useful Improvements in Bobsleds; and I do declare the following to be a full, clear, and exact description of the invention, such as will enable others skilled in the art to 10 which it appertains to make and use the same.

This invention relates to sleds, and especially the form of sled known as a bobsled.

One object of this invention is to provide 15 an improved sled which is exceedingly strong, rigid and durable and can be manufactured at a comparatively low cost.

Another object is to provide an improved knockdown sled which can very quickly and 20 easily be assembled by a child or other person of even less than ordinary ability.

Other objects and advantages may be apparent to persons who read the following details of description in connection with the 25 accompanying drawings in which:

Fig. 1 is a side elevation of my improved bobsled, the handle or tongue having a portion broken out and being turned backward.

Fig. 2 is a top plan view of the bobsled, 30 the tongue being broken off.

Fig. 3 is a transverse vertical sectional view along the lines 3—3 of Figs. 1 and 2.

Fig. 4 is a transverse vertical sectional view along the lines 4—4 of Figs. 1 and 2.

Fig. 5 is an enlarged detailed view, partly in side elevation and partly in section, of one of the sled-runners.

Fig. 6 is a longitudinal sectional detail, 40 the section being taken along the line 6—6 of Fig. 2.

Fig. 7 is a horizontal sectional detail, the section being taken along the line 7—7 of Fig. 4.

Referring to these drawings in detail, in 45 which similar reference characters correspond with similar parts throughout the several views:

The device comprises two pairs of runners 1 and 2 which are somewhat similar though 50 not identical in construction. A rear cross beam 3 connects the runners of the rear pair 1, and a front cross beam 4 connects the runners of the front pair. Moreover, the front ends of the rear pair of runners are 55 connected by means of a strut or bar 5 which is pivotally connected to these runners by

means of pins 6 retained in place by cotter keys 6', this bar 5 being an element of a link or coupling device which is loosely connected with the front cross beam 4 by a hook 7 which fits into an opening 4' formed in the front cross beam 4. Similarly, the front ends of the front runners 2 are connected by means of a strut or bar 8 which forms an element of the tongue member 65 which has a handle 9 on its free end, this bar 8 being also pivotally connected by means of pins 6.

All the main parts described in the foregoing are preferably made of malleable cast 70 iron and are all of I-beam construction, that is, the runners, for instance, are each formed with a web 10 and a marginal flange 11, this flange extending outward in opposite directions from the faces of the web 10, as 75 clearly illustrated in Figs. 3 and 4. The bottom portion of the flange 11 is apertured, as indicated at 12 in Fig. 5, to receive securing bolts 13 which extend therethrough from a runner-shoe 14. The inner ends of 80 these bolts 13 extend into apertures 15 which are formed in the web 10, and nuts 16 engage with these bolts 13 for securing the runner-shoe on the runner beam. The ends 85 of the runner-shoe may be interlocked with the flange 11 as indicated at 17 in Fig. 5.

Each runner is formed with uprights 18, and each of these uprights is formed with vertically extending ribs 19, a space or slot 90 20 being provided between the ribs 19 for receiving a narrow web 21 of the rear beam 3, or a somewhat similar web 22 of the front beam 4. The only substantial difference between the rear and front runners is that the ribs 19 of the latter are longer than those of the front beam. However, this difference 95 in the lengths of the ribs is not essential and the front and rear runners may be identical in construction. The upper portion of the flange 11 includes a U-shaped saddle which 100 is indicated at 23 in Figs. 3, 4 and 5, and this saddle of each runner receives and embraces a downward extension 3' of the rear cross-beam 3, each of the webs 21 being included in these downward extensions. How- 105 ever, the webs 21 fit within the slots 20, and this arrangement of the cross beams and their respective pair of runners prevents lateral and angular movements of the parts thus fitted together. The rear cross beam 110 is provided with recesses 24 which extend therethrough above the webs 21, and secur-

ing bars 25 are seated in the recesses 24 and have their ends secured to apertured lugs 26 of the runners by means of bolts 27 having nuts thereon. The front runners are provided with securing bars 25 and bolts 27, the latter extending through apertured lugs 26, these elements being substantially the same as described for the rear runners; but instead of front cross beam 2 being formed 10 with an aperture therethrough to receive the securing bar 25, this bar extends across the ends of the cross beam and is secured by the bolts 27. In this connection it will be noted that the front cross beam is lower than the 15 rear cross beam, and that a bolster 29 is secured thereon by means of a pin or bolt 30 which extends through the bolster and through the cross beam 4 and also through an eye in the hook 7 to loosely connect the 20 hook with the cross beam.

By the construction previously described, of the means of joining the crossbeams to the runner beams, these members are very strongly and rigidly united, and they may be 25 very quickly disunited by simply removing the bolts 27, detaching the bars 25 and then

lifting the crossbeams from the saddles of the runners.

What I claim as my invention is:

In a sled, runners each formed of a single casting and having a web portion provided with upstanding arms intermediate its length and a marginal flange extending transversely of the runner beyond its inner and outer side faces, the portion of the flange extending beneath the runner being reduced intermediate the length of the runner to provide a seat, a ground-engaging strip secured in said seat, ribs extending from the portions of the flange extending along the inner edges of said arms, and a cross bar for connecting said runners having each end provided with side grooves for receiving said ribs when the end portions of the cross bars are fitted between said arms, and strips carried by said arms and extending across the end portions of the cross bar to prevent upward movement of the cross bar.

In testimony whereof I have hereunto set 50 my hand.

OTTO J. NIENOW.
